UNITED STATES PATENT OFFICE

HERMANN M. HESSENBRUCH, OF ROSEMONT, PENNSYLVANIA, ASSIGNOR OF ONE-HALF
TO EDWARD L. DAVIS, OF PHILADELPHIA, PENNSYLVANIA

BENDING APPARATUS

Application filed June 4, 1926. Serial No. 113,604.

This invention relates to bending apparatus, more particularly to a type adapted to bending heavy rods or bars such as used to reinforce concrete in building construction. 5 Rods or bars of the kind referred to are used in different lengths, weights and shapes, and are bent to specifications which, aside from being very exacting, vary extensively in practice. To shape such bars it has been customary heretofore to chalk mark the blanks individually for guidance in bending according to specified measurements. With apparatus heretofore available, only one or two bends could be made at a time, especially 10 when operating upon the heavier stocks. Accordingly, work under such conditions is necessarily slow, costly and not always reliable as to accuracy, more particularly when production of successive duplicates is required.

The purpose of my invention is to overcome the various difficulties and drawbacks above pointed out by providing an efficient apparatus capable of being liberally adjusted 25 to accommodate blanks of any length, as well as to accurately predetermine the desired shapes in the finished bars, and of making the required bends all at the one time.

How the foregoing and other advantages 30 may be readily realized will be apparent from the detailed description hereinafter of the typical embodiment of my invention illustrated in the drawings; whereof Fig. I is a plan view—more or less diagrammatically represented—of the complete apparatus showing the various parts positioned in readiness to bend a bar or rod.

Fig. II is a similar view, with some of the detail omitted, showing the parts in positions assumed incidental to the bending of a bar or rod.

Fig. III is a plan view of one of the two component sections of the apparatus, on a larger scale than that of the preceding illustrations, with a portion broken away and in section to expose certain important details.

Fig. IV is an end elevation of one of the sections aforesaid viewed in the direction of the arrows IV—IV in Fig. III.

Fig. V is a side elevation of the section aforesaid, viewed in the direction of the arrows V—V in Fig. III; and

Fig. VI is a staggered fragmentary detail sectional illustration taken as indicated by the arrows VI—VI in Fig. III.

In the complete assemblies of Figs. I and II, the apparatus is shown as embodying two carriages comprehensively designated 10, 10 which, with the exception of being rights and lefts, are exact duplicates of one another. The carriages 10, 10 are shiftable along track rails 11, 11 by means of a differential screw 12, adapted to be rotated by a centrally-located actuating mechanism generally indicated by the numeral 13. This actuating mechanism 13 comprises a gear wheel 14 that is affixed to the screw 12 between stationary bearings 15, 15, and driven by a worm 16 on the shaft of a prime mover 17, in the present instance conventionally represented as an electric motor. A suitable reversing switch (not shown) is employed to control the motor 17 in order that the screw 12 may be driven in opposite directions to move the carriages 10 toward or away from each other as desired or required. As an aid to predetermine the spacing of the carriages 10 as aforesaid, one of the track rails 11 is graduated as shown at 18 in Figs. I and II.

In view of the similarity of the carriages 10, 10, the same reference characters will be used to designate corresponding parts, and, for the sake of brevity, such parts will, for the time being, be mentioned in the singular. With reference now more particularly to Figs. III, IV, V and VI wherein the right-hand end carriage 10 is illustrated to a larger scale than in the assembly views, 20 indicates the sub-platform or truck which is equipped with wheels 21 for traverse on the track rails 11, and has a depending threaded lug 22, engaging the corresponding end of the differential screw 12. Mounted on the truck 20 is a table whereof the L-shaped section 23 (Fig. III) is stationary, and the rectangular section 24 movable along the longer extremity 23^a of the first mentioned section toward and away from the shorter extremity 23^b of the latter. These table sections 23, 24, re-

spectively carry opposing groups of instrumentalities in the form of rollers 25, 25, 26, and 27, 28; adapted to engage a blank rod, such as shown at R, at different points along opposite sides incidental to bending it in a manner to be presently explained. Of the rollers comprising the first mentioned group, those marked 25, 25 are carried by a common slide 29 that is adjustable longitudinally in a head 30; while the one designated 26, is sustained in the laterally directed end of a bar 31, having pivotal connection at 32, with a supporting head 33, so that it may be swung upwardly and rearwardly out of the way when necessary. The heads 30, 33 are shiftable along a common longitudinal guide slot 34 in the extremity 23^b of the table section 23, and separately adjustable in accordance with suitable scale graduations at 35, Fig. III, by means of screws 36, 37 operable by an interchangeable crank handle 38. The rollers 27, 28 of the second group aforesaid are likewise adjustable in heads 39, 40, and said heads in turn separately shiftable in accordance with scale markings 41 along a groove 42 in the movable table section 24, by individual actuating screws 43, 44. The head 39 also permits swivel adjustment of the roller 27, through provision of a manually operable worm and gear couple 45. In addition to the appurtenances already described, the stationary table section 23 further supports a holding means having the form of clamp 46, that is adjustable along a groove 47, extending lengthwise of the extremity 23^a, and at right angles to the slot 34 and groove 42 for the roller heads 30, 33, and 39, 40. Here again, a hand screw 48 and graduated markings 49 are provided to facilitate adjustment. To determine proper positioning of the blank bars R in the apparatus, I employ a stop or limiting gauge 50, capable of being set in different positions along the inner edge of the shorter extremity 23^b of the table section 23.

The means for reciprocating the movable table section 24 include an electric motor 51, —Figs. IV and V—that is mounted on the platform 20, and, through speed reduction gearing 52, drives a shaft 53 journalled in a frame 54 which provides the supporting slide guideways 55, for the said movable table section. At the inner end, the shaft 53, has affixed to it a gear pinion 56, in mesh with a toothed rack 57 which is engaged in a rabbeted-groove 58, in the bottom of the movable table section 24, with capacity for relative adjustment, by aid of a screw 59, crank handle 60, and coordinated scale markings 61 along the contiguous edges of said movable table section and the extremity 23^a of the stationary section 23. In practice, the table section 24 is given a fixed movement and caused to make one complete reciprocation at each actuation. Such operation can be pre-

determined by use of suitable standard electrical appliances in the circuit including a reversing limit switch 62, and a stop switch 63, capable of actuation directly by the rack 57 of the table section 24 as it reaches the limit of its movements in opposite directions as conventionally indicated by the dot-and-dash lines in Fig. VI. It is to be particularly noted in this connection that the adjustment of the table section 24 with respect to the rack 57 permits regulation of the effective throw relative to the stationary table section 23 and the rollers 25, 26 carried thereby.

In use of the apparatus, the blank rod R is placed in the clamps 46 of the two carriages 10, its position, longitudinally, being determined through proper setting of the gauges 50, and sagging thereof prevented by a suitable roller support 62^a at the center, see Figs. I and II. The motors 51 on the carriages 10 are then simultaneously started to concurrently advance the movable table sections 24. As a result, the rollers 27, 28 and the movable table sections 24, 24 are first brought into contact with the corresponding side of the rod ends projecting beyond the clamps 46', and, in continued movement, cause such rod ends to be bent laterally about the outer corners of the fixed jaws of said clamps. As the operation proceeds, the rollers 26 on the stationary table sections next come into play, and, by cooperation with the roller 28, initiate angular terminal bends in the rod R. As the table sections 24, 24 approach the inward limit of movement (shown in Fig. II), the rollers 25, 25 on the stationary table sections 23 enter into action for final cooperation with the opposing rollers 27, 28. At this juncture, the limit switches 62 are tripped by the racks 57 associated with the movable table sections 24 to effect reversal of the motors 51 and return of said table sections to the normal retracted position of Fig. I. When the movement just described nears completion, the opposite ends of the table racks 57 trip the limit switches 63 to automatically stop the motors 51. As a consequence of such a cycle and the progressive action characteristic of the process, the bars R are fashioned to the configuration shown in Fig. II without imposition of longitudinal strain on the metal to cause stretching thereof. When the sharp terminal bends at b (Fig. II) are not required, the rollers 26 are withdrawn—from the sphere of activity—simply by swinging their supports 31 rearwardly about the pivotal connections 32 with the heads 33. By longitudinal adjustment of the heads supporting the several rollers 25, 26, 27 and 28, it will be obvious that the angle and length of the segment s of the rod R, as well as the proportions of the segments s' and s² may be varied to suit different requirements of practice. When a longer or shorter central span s² is desired, this may be had through relative shifting of the car-

riages 10 on the rails 11 by means of the differential screw 12.

Bends diversified as to depth (either the same or different at opposite ends of the bar 5 R) can be determined through positional adjustment of the clamps 46 and through variation in the effective throw of the movable table sections 24 obtainable by adjusting the latter with respect to their actuating racks 57.

10 From the foregoing it will be seen that with the apparatus of my invention, and by virtue of the capacity of its parts for diversified adjustment, it is possible not only to operate upon bars of different lengths, but to 15 bend such bars variously to suit the most exacting specifications. Moreover, by its use, batches of similar bars may be very economically produced with precision and rapidity 20 impossible of attainment by previous methods, or with the apparatus heretofore available, for bending purposes. It is of course to be understood that the principle of my invention may be embodied in apparatus for bending blanks other than bars such as specifically referred to herein, and the appended 25 claims are therefore to be interpreted with this thought in mind.

It is also readily conceivable that manually 30 or mechanically operable means may be substituted in lieu of the electric devices herein described for actuating the differential screw 12, as well as the movable table sections 24, without departing from the scope of the present invention.

35 Having thus described my invention, I claim:

1. In bending apparatus of the character described, the combination of means to stationarily grip a bar away from its ends, and 40 roller instrumentalities capable of individual adjustment for alternately engaging the free ends of the bar at different points along opposite sides to effect progressive bending without inducing longitudinal strain in said bar.

2. In bending apparatus of the character described, the combination of roller instrumentalities for engaging the free ends of a 50 bar at different points along opposite sides, said instrumentalities being individually adjustable in a common plane, and means for moving said instrumentalities relatively to bend the bar.

3. In bending apparatus of the character 55 described, the combination of counterpart instrumentalities for engaging the free ends of a bar at different points along opposite sides, said instrumentalities being individually adjustable in a horizontal plane with respect to one another, and means for moving 60 said counterpart instrumentalities relatively to bend the bar.

4. In bending apparatus of the character 65 described, the combination of right-and-left hand sets of instrumentalities for engaging

the free ends of a bar at different points along opposite sides, the individual instrumentalities of each set being adjustable positionally in a common plane and collectively adjustable with respect to those of the other set, and means for moving the respective sets of said instrumentalities relatively to bend the bar. 70

5. In bending apparatus of the character described, the combination of holding means, opposed sets of instrumentalities for engaging a bar along opposite sides, each of said instrumentalities being positionally adjustable to engage said bar at different points of its length, and means for moving the respective sets of said instrumentalities and the holding 75 means relatively to bend the bar. 80

6. In bending apparatus of the character described, the combination of holding means for gripping a bar away from the ends thereof, right-and-left hand sets of instrumentalities for engaging the free ends of said bar at different points along opposite sides, and means for moving the engaging instrumentalities and the holding means relatively to bend the blank, said engaging instrumentalities being individually adjustable along the length of said bar. 90

7. In bending apparatus of the character described, the combination of holding means for gripping a bar at points away from the ends thereof, right-and-left hand sets of instrumentalities for engaging free ends of said bar at different points along opposite sides, means for moving the respective sets of instrumentalities and the holding means relatively to bend the bar, and said instrumentalities being positionally adjustable individually and collectively with respect to the holding means. 100

8. In bending apparatus of the character described, the combination of holding means for gripping a bar at points away from the ends thereof, right-and-left hand opposing groups of instrumentalities for engaging the free ends of said bar at different points along opposite sides, means to enable positional adjustment of the instrumentalities of each group relatively as well as with respect to those of the other group, means enabling adjustment of the holding means relative to both groups of the instrumentalities aforesaid, and means for moving the respective opposing groups of instrumentalities relatively and with respect to the holding means in bending the bar. 105 110 115

9. In bending apparatus of the character described, the combination of holding means for rigidly gripping a bar at points away from the ends thereof, opposing groups of individually adjustable instrumentalities for engaging the bar at different points along opposite sides of the free ends of said bar, and means for moving one of said groups to bend the bar while the other group of said instrumentalities remains in a stationary position. 120 125 130

10. In bending apparatus of the character described, the combination of two similar carriages adjustable in a longitudinal direction, each said carriage bearing opposing groups of instrumentalities for engaging a bar at different points along opposite sides near the ends thereof, the individual instrumentalities of each group being positionally adjustable about a horizontal plane, and associated means for moving some of the instrumentalities aforesaid relatively to effect bending of the bar ends in right-and-left hand directions.

15 In testimony whereof, I have hereunto signed my name at Philadelphia, Pennsylvania, this 1st day of June, 1926.

HERMANN M. HESSENBRÜCH.
